ARNOLD NESBITT MACNICOL, OF MELBOURNE, VICTORIA, AUSTRALIA.

CLEANING APPARATUS.

1,122,963.

Specification of Letters Patent. Patented Dec. 29, 1914.

Application filed November 30, 1912. Serial No. 734,337.

To all whom it may concern:

Be it known that I, ARNOLD NESBITT MACNICOL, a citizen of the Commonwealth of Australia, residing at 31 Queen street, Melbourne, in the State of Victoria, Commonwealth of Australia, have invented new and useful Improvements in Cleaning Apparatus, of which the following is a specification.

10 This invention relates to an apparatus for cleaning and scraping iron, steel and other surfaces, being specially adapted for cleaning and scraping the sides and bottoms of ships when in the water or in dock.

15 The essential features of this invention comprise means whereby the apparatus is self-propelled and reversible, being held to the side of the ship or other surface while traveling over the surface while the scraping and cleaning operation is being performed. Suitable steering mechanism is provided to retain the apparatus in the line of travel.

20 The apparatus is held to the surface to be cleaned either by electro-magnets or by the reaction of a water jet produced by means of a pump or the water may be led to the jet by a hose or like connection in any suitable manner.

25 The electro-magnets are provided with rotating pole pieces which are driven by suitable gear from the source of power. The power for driving is derived from a compressed air engine, electric motor or other driving element positioned preferably within and driving the rotating cleaning brush. Power may be conveyed to the apparatus by means of flexible shafting. Alternatively, the appliance may be held to 30 the surface to be cleaned or cleaned and scraped by the action of a pump operated by the driving element and arranged to eject the water from the interior of the frame and to force it away at approximately right angles to the surface to be 35 cleaned, or a jet may be provided receiving the water from an external source by means of a hose or like connection.

40 In order that the invention may be more readily understood it will now be described with reference to the accompanying drawings illustrating the invention adapted for cleaning and scraping the sides and bottoms of ships.

Figure 1 is a side elevation of a vessel having an appliance constructed according to this invention mounted thereon. Fig. 2 is a plan, and Fig. 3 is a side elevation of the preferred form of apparatus, where electromagnets are employed, constructed according to this invention and the apparatus being reversible is fitted with suitable steering mechanism. Fig. 4 is a side elevation of another form of apparatus constructed according to this invention. Fig. 5 is a sectional elevation of a modification, wherein the apparatus is held to the surface to be cleaned by the action of a pump. Fig. 6 is a transverse section of the cleaning brush illustrating the internal compressed air motor. Fig. 7 is a sectional elevation of the compressed air engine illustrated in Fig. 6. Figs. 8 and 9 are detail views illustrating centrifugal scrapers constructed according to this invention. Fig. 10 is a side elevation of a reciprocating scraper constructed according to this invention. Fig. 11 is a detail view of the driving sprocket carried by the brush. Fig. 12 is a side elevation of the apparatus illustrated in Fig. 4 having the scrapers attached thereto. Fig. 12^a is a view in plan illustrating the scrapers fitted to the apparatus.

Like reference numerals indicate the same or corresponding parts in all the figures.

As illustrated in Figs. 2 and 3, one form of the invention consists essentially of one or more electromagnets 1 mounted upon a suitable frame. When more than one magnet is employed they are suitably distanced from each other by a non-magnetic or other suitable frame 2 preferably constructed of light material such as aluminum. The magnets 1 are fixed to the center of U or other shaped cores 3, the ends of which project at right angles to the frame 2, and are provided with rollers or runners 4 adapted to normally rest against the ship's side or other surface to be cleaned and from rotating pole pieces. Suitable eyes 5 are provided at the ends of one of the cores 3 which connect with suitable tackle for raising, traversing or lowering the appliance as hereinafter described.

As illustrated in Fig. 2, revolving brushes 6 and 6^a are mounted at either end of the machine frame 2 immediately outside the

cores 3 of the magnets 1. These brushes 6, 6^a extend the width of the frame and are preferably revolved by a compressed air engine 7 either fixed in the interior of one of the brushes 6, as illustrated in Fig. 6, or in an external position, in which case the brushes 6, 6^a would be driven by chain and sprocket or other gear. It is preferred, however, that the compressed air engine 7 be positioned within the rotating brush 6, the cylinders being adapted to rotate around a crank shaft through which the air is conveyed to the engine. The other brush 6^a is driven by a chain and sprocket or other gear hereinafter more fully described. The engine 7 consists of two or more cylinders 8 attached to the inner surface of and within the brush frame 9. The pistons 10 are actuated by the compressed air fed from a convenient source of supply, through a flexible or other connection 11, to a partially hollow crank shaft, the flexible connection being fitted to a suitable union or mouth piece 13 at the inlet end 14 of the shaft. The piston rods 16 are mounted upon a solid portion 15 of the crank shaft between the inlet and exhaust ports thereof. The crank shaft consists of a hollow spindle 17, except that portion 15 of the shaft to which the connecting rods 16 are attached. This hollow shaft acts as the inlet and exhaust pipe as well as a rotary valve, doing away with complicated valve mechanism. Suitable ports and connections 20 are provided on either side of the crank leading to each inlet port of the cylinders, the exhaust ports 21 thereof being connected to the opposite side by a suitable connection 22 to a corresponding and larger orifice or port 23 on the opposite side of the crank. The ports are so timed and positioned that each cylinder receives the required amount of gas at the proper time and the exhaust orifices are of greater length to allow of the exhaust gases to be discharged quickly and allow the cylinder to go to the top of its stroke for the next charge, thus providing suitable power propelling mechanism for the brushes 6, 6^a, the rotating pole pieces 4 of the apparatus, and, if desired, the driving rollers 60 on the rope 55 as illustrated in Fig. 3. If desired, the hollow shaft may be adjustably mounted to the frame 2. It will be readily understood that in lieu of the compressed air engine, the brush or brushes may be driven by an electric motor internally mounted within the brush frame, or as illustrated in Fig. 3 the electric motor 24 is mounted in a convenient position upon the frame 2.

The appliance may be used for scraping purposes, either apart or in combination with the brushes, in which case a series of scrapers 25 eccentrically mounted and having a reciprocating motion are fitted to a

shaft mounted in brackets 26 in front of the brushes 6, 6^a. The scrapers or fingers 25 are adapted to be pressed to the surface to be cleaned by suitable flat springs 26^a connected to the brackets 26 and bearing 70 on the upper edge of the connecting rods 27 carrying the scrapers 25. Each scraper consists of a plate 25 arranged diagonally and having a beveled or chamfered scraping edge 28. The lower ends of the connecting rods 27 pass through slotted lugs 29 formed across the upper surface of the scraper or plate 25 and carry helical springs 30 between these lugs to act as buffers when the plate meets an obstruction, the end of the 80 rod being held by a nut 31 bearing against the lower lug as illustrated. The connecting rods 27 are mounted on a suitable shaft 32 driven by a chain 33 and sprocket 34 from the brush frame 9 of the brushes 6, 6^a, the sprocket 35 being mounted to a suitable sleeve or distance piece 36 attached to the brush frame.

In order that the scrapers may override any obstruction that may be encountered, each scraper 25 is provided on either side with bent arms 37 extending past the front edge thereof and carrying suitable rollers or runners as 38 at their outer ends. These rollers or runners 38 are of suitable length 95 and are adjustably mounted in slots 39 formed in the arms 37, the rollers being normally set a slight distance above the line of the edge of the scrapers 25 as illustrated in Figs. 4 and 12. This arrangement will 100 allow the scrapers to override any rivets, nuts or other metal obstructions, the springs 26^a and 30 acting as buffers to absorb any shocks that may be imparted to the scrapers 25.

In lieu of the reciprocating scrapers 25 centrifugal scrapers 40 may be employed. These centrifugal scrapers 40 are mounted upon a shaft 41 driven by the sprocket 34 on the shaft 32. These scrapers 40 may be 110 suitably distanced around the shaft, any suitable number being used. The scrapers consist of sleeves 40 adapted to slide upon a head 43 mounted on a square spindle 44 fitted to the shaft 41. The base of the sleeve is 115 tapered to a knife or other edge 45 for scraping the surface to be cleaned. When any obstruction is encountered such as rivets, nuts or the edge of a plate, the sleeves 40 are adapted to slide upon the head 43. Instead 120 of using reciprocating or centrifugal scrapers, they may be loosely attached to a suitable spindle or shaft mounted to the front of the frame and having the above described bearing and buffer springs to retain 125 them in contact with the surface to be cleaned. The scrapers may be positioned so that each one is projecting slightly to the front of the other.

The revolving pole pieces 4 of the electro- 130

magnets may be driven from the brush frame 9 by suitable gear in such a manner that the appliance slowly traverses the surface to be cleaned. In order to attain this object, suitable reduction gear 46 (Figs. 3 and 4) is provided preferably arranged in a gear box 47 mounted on the frame 2, the gear being reduced to provide the necessary traveling speed. For heavy work a secondary chain 48 and sprockets 49 could be brought into action and the remaining set of pole pieces 4 rotated. Either the forward or rear rotating pole pieces 4 or both may be driven as desired.

The apparatus is adapted to travel continuously backward and forward over the surface to be cleaned, the machine being suspended and guided or moved over the surface as illustrated in Fig. 1 of the accompanying drawings. The eyes 5 fitted to the core 3 are connected to the ropes, chains or other connections 50 suspended from a carrier 51 carrying grooved rollers or runners 52 mounted upon a ledge or projection 25 formed on a bar 53 fitted to and extending around the waist of the ship. A vertical post 54 is adjustably mounted at either end of the ship upon which a fixed rope, chain or rod 55 is adapted to slide, the vertical movement thereof being controlled by a hand or other winch 56 positioned at each end of the ship. The rope 55 is supported at suitable distances along the length of the ship by means of brackets or connections 57 having a tubular extension or sleeve 58 adapted to hold the rope. These connections 57 are adapted to be raised and lowered correspondingly to the fixed rope 55.

A bracket or support 59 extends from the frame 2 and carries a series of grooved pulley wheels or guide rollers 60, a fixed rope 55 passing between each pair of rollers 60, the lower rollers being operated or driven from the reduction gear 46 by means of sprocket wheels 61 and chains 62 and 63. In this way, the appliance would traverse the surface to be cleaned from end to end or around it and mechanism may be embodied for keeping the appliance in line with the rope 55 by regulating or steering gear which consists of a series of connecting arms 64 connecting each of the spindles 65 of the rotating pole pieces and controlled centrally by means of the pivoted levers 66 projecting up through the frame toward the front and rear of the machine as illustrated in Fig. 3, and which are provided with pivoted extensions 67 having bifurcated ends 68 adapted to engage the rope 55. In practice, one of these extensions 67 is not in use according to which direction the machine is traveling, one being used when the machine is traveling forward and the other on the reverse motion of the machine. For this purpose the extensions are pivoted

at 69 in such a manner as to allow the extension 67 to drop back out of engagement with the rope 55. In order that the pole pieces may be effectively steered, the ends 70 of the cores 3 carrying the pole pieces are swiveled or pivoted at 71 in any suitable manner.

As illustrated in Figs. 2 and 3, the brushes 6 and 6^a are mounted upon the brackets 72 extending outwardly from the frame 2 and this bracket 72 may be provided with an extension 73 (Fig. 12) adapted to carry the reciprocating or centrifugal scrapers 25 and 40 as above described.

In the modification illustrated in Fig. 4, the brush 6 is mounted within the frame 2 between the magnets, but should this form of construction be employed, it is preferred that a smaller brush (Fig. 12) is mounted between the scrapers 25 and the rotating pole pieces 4 in order to partially clean the surface before contact is made by the pole pieces 4 with the surface to be cleaned. In order to counteract the effect of gravity when working under water, a float 74, preferably consisting of a cylinder, which may be collapsibly arranged if desired, is adjustably mounted on the machine frame 2 in a convenient position by straps 75 or the like. The float may be of a size and capacity to raise the appliance to the surface as soon as the appliance has moved from the vessel and the magnetic field has ceased to act on the surface. If necessary, the appliance or any part thereof may be provided with a suitable casing or cover.

In lieu of the electro-magnets above described, the appliance may be kept to the surface to be cleaned under water by the action of a pump as illustrated in Fig. 5. This pump 76 is preferably centrally positioned above the main brush on the top of the casing or cover 77 of the appliance to the side of and operated by the driving element, either a compressed air engine 7 or an electric motor 24 above described.

The main brush 6 is positioned transversely of and within the frame 77 and the spindle 78 thereof is mounted in bearings on the said carrying frame. The brush receives its motion from the driving element, in this instance positioned on the top of the casing or frame by a chain 79 and sprocket wheels 80 and 81 in turn connecting by suitable reduction gear 82 and the chain 83 and sprockets 84 and 85 with a pair of rollers or runners 86 mounted in bearings 87 at the rear of the frame 77. A second pair of rollers 88 are fitted to the forward or front end of the frame 77 and the rollers 86 and 88 are adapted to contact with the surface to be cleaned. If desired, the front rollers 88 may be driven from the rear rollers by the chain 89 and sprockets 90 and 91. At each end of the machine a smaller brush 92 is

fitted and this brush is rotated by the chain 93 and sprockets 94 and 95 from the main brush, or in any other suitable manner.

The rollers or wheels are driven at a suitable speed by the reduction gear 82 arranged in a gear box if desired. The frame or casing 77 of the appliance is preferably adapted to project past the rollers as illustrated at 96, and this casing is not in contact with the 10 surface to be cleaned, thus allowing a sufficient volume of water to pass between the edge thereof and the surface into the casing. The pump 76 is arranged to eject the water from within the casing 77 and force 15 it away at approximately right angles to the surface to be cleaned as illustrated in Fig. 5 thereby forcing and retaining the appliance close to the surface, the water being pumped from the interior of the casing or frame 77 causes a partial vacuum which tends to force the appliance against the 20 cleaning surface. The frame 77 is provided with brackets 62 carrying the grooved pulley wheels 60 which are driven as illustrated in Fig. 3 and retained in position upon the fixed rope 55. It will be readily understood that the steering appliances may also be fitted as above described and the scrapers 25 may be mounted upon the frame 77 25 in any suitable and convenient manner. The scrapers 25 may also be used instead of the leading brush 92. The steering appliances preferred consist of arms 108 fitted to each end of the frame 77 and extending 30 vertically where they engage the rope 55 by means of the forked or bifurcated ends 109.

An indicator may be provided adapted to determine the depth of the appliance under the water line and this indicator may be 40 fitted to the frame 2 in any suitable manner. The indicator preferably consists of a light telescopic tube held by suitable supports, the upper end being adapted to project above the water. When two brushes 45 are employed, one may be geared to travel in the opposite direction to the other so as to regulate the speed at which the machine traverses the surface, and in order to attain this object, one brush is caused to revolve 50 at a greater speed. This motion may be attained by suitable gear wheels from the brush and may be used with or without the reduction gear driving the revolving pole pieces.

55 The driving gear consists in the case of Fig. 2 of the internal compressed air engine 7 arranged within the frame of the brush 6 and operating the brush 6^a by means of the chain 97 and sprocket wheels 98 and 99, the 60 sprocket 99 being mounted on a suitable flanged sleeve 100 on the brush frame. The scrapers employed are driven by means of the sprocket 34 driving the shaft 32 in any suitable manner, while the pole pieces are

rotated by means of the reduction gear 46 65 positioned in the gear box 47 in a manner similar to that illustrated in Fig. 4, the pole pieces being driven by the chain 101 and sprocket 102 on the pole piece spindle direct from the reduction gear. A secondary 70 chain 103 and corresponding sprocket 104 may be used adapted to drive the other pair of rotating pole pieces in any convenient manner.

In Fig. 3 the driving element consists of 75 an external electric motor 24 adapted to drive the rear brush 6^a by means of the reduction gear 46 and a chain 101 gearing with the sprocket upon the brush frame or spindle. The front brush is driven from 80 the rear brush by a suitable chain 105 gearing with a sprocket 106 on the front brush spindle and corresponding sprocket on the rear or driving spindle. The pole pieces are rotated by means of the chain 107 from 85 the rear brush, while the front pole pieces are rotated by the secondary chain 48 and corresponding sprockets mounted upon the rotating pole spindles. The chains 62 and 63 are adapted to drive the guide rollers 90 60 from the reduction gear 46.

As illustrated in Fig. 5, the machine is driven from the compressed air engine or electric motor positioned upon the frame 77 which drives the pump 76 and also the main 95 brush 6 by means of the chain 79 and sprocket 80. Suitable reduction gear 82 is also provided and drives the rear roller or wheel 86 by means of the sprockets 84 and 85 and the chain 83. The front roller is 100 driven by the chain 89 and sprockets 90 and 91 from the rear rollers 86. The brushes 95 are driven by means of the chains 93 and sprockets from the main brush 6.

With an appliance constructed as above 105 described, it will be readily understood that on the traveling of the appliance over the surface to be cleaned the magnets, or water jet, will hold the machine against the sides of the ship or other surface. On being set 110 in motion the brush or brushes with or without the scrapers will effectually clean the surface in an efficient manner, the driving rollers 60 being adapted to drive the appliance either backward or forward over the 115 surface to be cleaned in the manner above described.

What I claim as my invention and desire to secure by Letters Patent is:—

1. An apparatus for cleaning iron, steel 120 and other surfaces, and especially adapted for cleaning the sides and bottoms of ships, comprising a casing, a pump mounted upon the casing and adapted to pump water from within the casing, whereby the apparatus is 125 held against the surface to be cleaned.

2. An apparatus for cleaning iron, steel and other surfaces and especially adapted

for cleaning the sides and bottoms of ships when in the water, comprising a casing, a pump mounted upon said casing, means for actuating the pump to force water from within the casing, whereby the apparatus is held against the surface to be cleaned, and driving means for propelling the apparatus over said surface.

3. An apparatus for cleaning iron, steel and other surfaces comprising in combination a frame carrying cores with electromagnets mounted thereon and provided with rotating pole pieces, rotating brushes, actuating means for said brushes suitably positioned adapted to drive the brushes, means for driving the pole pieces at a suitable speed consisting of suitable gear, scrapers fitted to said main frame and driven from the brush frame and a float adapted to counteract the effect of gravity when working under water, substantially as and for the purposes specified.

4. An apparatus for cleaning iron, steel and other surfaces, specially applicable for cleaning the sides and bottoms of ships when in water consisting of a brush inclosed in a frame or casing carrying rotating wheels or rollers adapted to bear against the surface to be cleaned, a pump and discharge nozzle mounted outside said frame and at right angles thereto actuated by a driving element, the pump being adapted to eject and deliver the water from within the casing and so retain the appliance to the surface to be cleaned, in combination with means for driving the brush within the casing and the rollers on the frame, scrapers fitted to said frame and brushes secured at the front and rear of the frame adapted to be actuated in any suitable manner, means for propelling the appliance over the surface to be cleaned, such as driving rollers fitted to the frame and carried by a fixed rope or chain fitted to the side of the ship substantially as and for the purposes specified.

5. In apparatus for cleaning iron, steel and other surfaces, reciprocating scrapers comprising a beveled or chamfered plate provided with lugs adapted to carry one end of a connecting rod, a spring mounted upon said rod, the rod being eccentrically mounted upon a driven shaft or spindle, a guide or lifting roller mounted upon arms projecting forwardly from the scraper, a flat spring adapted to bear against the upper surface of the connecting rod substantially as and for the purposes specified.

6. In apparatus for cleaning iron, steel and other surfaces, a rotating brush having a compressed air engine mounted therein and adapted to rotate around a crank shaft, the shaft being partially hollow to receive the air supply and is adapted to feed the

gas into the cylinders fixed to the brush frame, a solid portion of the shaft dividing the exhaust and delivery connections of the cylinders, inlet and exhaust orifices therefor and pistons mounted within the cylinders the piston rods being carried by the shaft substantially as and for the purposes specified.

7. In an apparatus for cleaning iron, steel and other surfaces, means for raising, traversing and lowering the apparatus which is suspended by suitable flexible connections from a carrier having grooved pulleys or rollers mounted upon a projecting ledge fitted around the waist of the ship or other surface to be cleaned, vertical posts arranged at each end of the ship carrying a fixed rope adapted to be vertically adjusted which passes through or around grooved pulleys or rollers fitted to the machine frame, the rollers being driven from the driving element, and steering levers connecting the fixed rope to keep the appliance in line with the direction of travel substantially as and for the purposes specified.

8. An apparatus for cleaning iron, steel and other surfaces, comprising a frame, carrying electromagnets and cleaning and scraping mechanism, the said magnets being provided with driven pole pieces adapted to contact with the surface to be cleaned, the said pole pieces being loosely mounted on the cores of said magnets and steering levers adapted to be connected by said pole pieces.

9. An apparatus for cleaning iron, steel and other surfaces comprising in combination a frame, rotating brushes mounted thereon, means for holding the apparatus to the surface, scrapers mounted to said frame, raising, lowering, traversing and steering mechanism, a float, an indicator to determine the depth of the appliance when working under water, and means for driving the apparatus over the surface to be cleaned substantially as and for the purposes specified.

10. In apparatus of the class described, a rotating brush, the driving element being mounted within the brush frame, a flanged sleeve carrying a gear wheel adapted to impart motion to a second or other brushes substantially as and for the purposes specified.

11. In apparatus for cleaning iron, steel and other surfaces, a frame carrying guide rollers at each end adapted to contact with the surface to be cleaned, the rollers being pivoted to the frame and connecting steering levers adapted to connect with a fixed rope or other connection, a cleaning brush mounted within said frame, means for imparting motion to said brush, a pump or water jet for holding the apparatus to the

surface to be cleaned, guide rollers connecting with the said fixed part and means for driving said guide rollers substantially as and for the purposes specified.

5 12. In apparatus for cleaning iron, steel and other surfaces, a frame having outwardly projecting steering levers positioned at each end thereof, the said levers being forked to engage a fixed rope or chain in

contact with driving rollers fitted to the said frame substantially as and for the purposes specified. 10

In testimony whereof I affix my signature in the presence of two witnesses.
